UNITED STATES PATENT OFFICE

ALBERT P. FISKE, OF HOHOKUS, NEW JERSEY

PIPE HOLDER

Application filed June 3, 1932. Serial No. 615,144.

The present invention relates broadly to smokers' articles and more especially to a pipe holder for smokers' pipes.

The invention is characterized more especially by a supporting member provided with a recess having an opening in the bottom thereof and with the walls of the recess comprising inverted frusto-conical shaped ends with one end being smaller than the other and opposed walls joining said ends by substantially tangent straight line planes inclined to the vertical to form opposed supporting surfaces adapted to hold pipes of different sizes. Where straight stemmed pipes are supported in said holder, the stem occupies an upwardly and outwardly inclined position with the bowl of the pipe resting in the large portion of the recess.

More specifically, the preferred form of the pipe holder comprises a hollow walled supporting member with a recess to receive a pipe and having substantially straight inclined side walls leading downwardly to an opening which prevents the collection of dust and ashes in the pipe holder. The configuration of said side walls presents an oblong shaped recess adapted to receive pipes of different sizes and to support the same against upsetting since the weight of the pipe tends to cause the pipe to slide downwardly on the straight line supporting walls to set the bowl of the pipe in a substantially vertical position.

It is recognized that the disclosure herein may be departed from without departing from the invention, and, therefore, the specific disclosure is to be understood as illustrative and not in the limiting sense.

Fig. 1 is a plan view of a preferred form of pipe holder.

Fig. 2 illustrates a vertical section taken on line 2—2 of Fig. 1.

Fig. 3 is a plan view of the pipe holder inverted.

The preferred embodiment of the pipe holder comprises a hollow body preferably formed of a moldable material and comprising side walls 1 forming a supporting base and a top wall 2 connected with said side walls. A recess is formed in the top wall 2

and is provided with inclined sides which preferably lead downwardly to an opening 5. One end of the recess is formed on a large curvature 6 and the other end of the recess may be formed on a small curvature 7; the inclined walls 4 of the recess extending between the large curved end 6 and the small curved end 7 are preferably substantially straight planes, so that there are no curved parts on the recess walls 4 to interfere with the reception and support of a smoker's pipe therein. The degree of inclination of the recess walls is substantially 25° as measured from a line at right angles to the base, as is indicated in Fig. 2. Preferably, the vertical height of the inclined recess walls is less than the height of the supporting side walls and preferably, the inclined recess walls are cut away at the point 8 to prevent the inclined walls in the small portion of the recess from contacting at the bottom of the recess to form a dust catching trough.

Fig. 2 illustrates a smoker's pipe 9 in dotted lines in the holder, and such a pipe will contact with the inclined walls, thereby holding the pipe upright due to its weight tending to slide the pipe downwardly to the lowest position of rest.

The present invention is preferably constructed of light weight material and comprises smooth side walls throughout which, together with the open bottom in the recess, prevents the collection of any dust or ashes that not only are unsanitary and unsightly, but which mar the polish on fine pipes. The inclined recess walls are preferably generated on straight lines so as to accommodate all normal sizes of smokers' pipes and while the pipe holder is particularly well adapted for straight stem pipes, it holds curved stem pipes with equal facility, thereby preventing the pipes from rolling and spilling ashes over tables or table drapes. When a pipe is laid in the holder, the pipe is securely held from rocking because the weight of the pipe forces the same down against the straight line inclined walls and the 25° inclination is such as to prevent any possible tipping of more than 25° from the vertical. However, in the majority of cases, the pipe pivots on the

stem so that the bowl assumes a substantially vertical position of much less than 25° inclination to the vertical.

Furthermore, since the inclined side walls 5 of the recess converge from the large end of the recess toward the small end thereof, a pipe placed in the recess some distance from the large end thereof will slide longitudinally in an upright position until it comes to rest 10 against the end wall at the large end of the recess, thus preventing the spilling of the contents of the pipe even if very carelessly laid on the holder.

What I claim is:

15 1. A smoker's pipe support comprising a body portion having a pipe supporting recess therein, said recess comprising a large semi-circular configuration at one end thereof and a small semi-circular configuration at the 20 other end thereof, with the inclined supporting walls of said end configuration, each comprising substantially one-half of a frustum of an inverted cone, and inclined walls between the halves forming tangents to the sides of 25 said halves.

2. A smoker's pipe support having a body portion, said body portion being open at the bottom thereof and having a recess in the top thereof, said recess having pipe-supporting 30

converging side walls inclined upwardly and outwardly and having plane surfaces, and curved end walls having the same inclination as the side walls, said side and end walls of said recess adapted to have only two point or single line contact with the bowl of the pipe supported therein.

3. A smoker's pipe support for pipes having curved bowls, said support having a substantially triangular recess, the sides and ends of which are inclined downwardly and inwardly, the angle of inclination being the same at all points whereby a pipe placed in said support would have only three point or linear support at its bowl end and two point 80 support adjacent its mouth piece end.

4. A smoker's pipe support comprising a body having a recess in the top thereof, said recess having a curved end wall sloping downwardly and inwardly, side walls of substantially the same downward and inward inclination diverging outwardly from the curved end wall in substantially straight lines and connected to another curved end wall of substantially the same downward and inward 85 inclination, said recess being open at its bottom.
